BOOM MECHANISM FOR DIGGING MACHINES

Alvin W. Acker, Topeka, Kans., assignor to Henry Manufacturing Company, Inc., Topeka, Kans., a corporation of Kansas

Application September 15, 1954, Serial No. 456,161

3 Claims. (Cl. 214—138)

This invention relates to new and useful improvements in boom mechanisms for digging machines, and has particular reference to digging machines wherein a bucket, shovel or other digging member is carried at the end of a vertically pivotal boom, and operable by the movement of said boom to be lowered to a digging position below the ground level, and raised to a dumping position above the ground level.

The principal object of the present invention is the provision of a boom mechanism of the class described wherein the length of the boom is automatically increased as it is lowered to its digging position, and decreased as it is raised to its dumping position. This provides for the digging of holes, ditches or the like to a greater depth below the level on which the digging machine is positioned, without at the same time increasing the height of the machine when the boom is raised to its dumping position. Many similar machines are dangerously top-heavy when the boom is raised, exerting great stresses on the boom mountings, and being apt to tip over, especially when being transported over roads at substantial speeds. The arrangement also requires less power to operate the boom, since the boom length, and consequently the moment arm of the load carried thereby, is steadily decreased as the load is raised. The arrangement also permits the digging of vertical-walled holes closer to the digging machine and hence within full view of the operator, since the boom is relatively short when the digging depth is shallow, and progressively lengthens as the depth increases.

Another object is the provision of a boom mechanism of the character described wherein both the raising and lowering of the boom, as well as the lengthening and shortening thereof, is accomplished by a single power unit.

Other objects are extreme simplicity and economy of construction, efficiency and dependability of operation, and adaptability for use with many pre-existing types of digging machines.

With these objects in view, as well as other objects which will appear in the course of the specification, reference will be had to the drawing, wherein:

Fig. 1 is a side elevational view of a boom mechanism for digging machines embodying the present invention, showing the boom and related parts in a raised position in solid lines and in a lowered position in dotted lines, and showing the digging bucket in various positions in dotted lines.

Fig. 2 is an enlarged sectional view taken on line II—II of Fig. 1.

Like reference numerals apply to similar parts throughout the several views, and the numeral 2 applies to a frame of any suitable construction which is customarily mounted on a tractor or other supporting vehicle. Said frame may also be raised above the ground for transportation, or lowered against the ground, which is indicated at 4, for added stabilization and support. Said mounting and elevating means, however, form no part of the present invention and are not here shown. A boom-

2

supporting standard 6 is carried in a vertical position by frame 2. Said standard is axially oscillatable on bearing members 8 carried by frame 2, and suitable means may be carried by the frame for oscillating said standard. 5 However, this feature forms no part of the present invention and said oscillating means is not shown.

The boom 10 comprises an inner end section 12, and an outer end section 14 telescoped slidably over section 12. Said boom sections are non-circular in cross-sectional shape (square as shown) in order to prevent relative rotation thereof. The inner end of section 12 is pivotally attached at 16 to a bracket 18 welded or otherwise fixed to standard 6. A hydraulic boom cylinder 20 disposed beneath and parallel to the beam is pivoted at 22 to a bracket 24 fixed to boom section 12. Said hydraulic cylinder is provided with a piston 26 movable therein, and a piston rod 28 fixed to said piston and extending forwardly from said cylinder, the outer end of said piston rod being pivoted at 30 to a bracket 32 welded or otherwise fixed to boom section 14. Cylinder 20 is double-acting, the piston 26 therein being movable in either direction by the delivery of pressure fluid selectively to the hydraulic connections 34 and 36 at either end thereof. A rigid link 38, I-shaped in cross-sectional contour, is pivoted at one end to bracket 32 at 40, and at its opposite end to bracket 42 at 44, bracket 42 being welded or otherwise fixed to standard 6 in spaced apart relation below bracket 18.

A bucket arm 46 is provided intermediate its ends with a bracket 48 fixed thereto, said bracket being pivoted at 50 to the outer end of boom section 14. A bracket 52 is fixed to the upwardly extended end of said bucket arm, and is pivoted at 54 to a piston rod 56 which is attached to a piston 53, movable in a double-acting hydraulic cylinder 60 having hydraulic connections 62 and 64 at the ends thereof. Said cylinder is pivoted at 66 to a bracket 68 fixed to boom section 14 at the inner end thereof.

A bucket or shovel 70 which opens toward boom 10 is pivoted adjacent its open side, at 72, to the downwardly extended end of bucket arm 46. A toggle link 74 is pivoted at one end to bucket 70 at the back or closed side thereof, as at 76, and at its opposite end is pivoted at 78 to one end of link 80, the opposite end of link 80 being pivoted at 82 to bucket arm 46 in spaced apart relation above bucket pivot 72. A piston rod 84 is pivotally connected at 78, and is fixed to a piston 86 movable in a double-acting hydraulic cylinder 88 provided with hydraulic connections 90 and 92, said cylinder being pivoted at 94 to bracket 52 at the upper end of the bucket arm. The axes of all of the pivots 16, 22, 30, 40, 44, 50, 54, 66, 72, 76, 78, 82 and 94 are parallel and generally horizontal. The hydraulic system for energizing each of the cylinders 20, 60, and 88 is conventional, and is not here shown. In general, the system comprises suitable pumping and valving means mounted on frame 2 and driven by the engine of the tractor or other vehicle supporting said frame, through suitable driving connections.

In operation, hydraulic cylinder 88 serves to pivot the bucket 70 with respect to bucket arm 46, acting through toggle-linkage 74—80. Said toggle linkage serves to provide a greater pivotal arc for the bucket with less movement of the hydraulic piston, thus permitting the use of a shorter cylinder and promoting economy. Cylinder 60 serves to pivot bucket arm 46 relative to the boom. To lower the boom, fluid is fed to cylinder 20 through fluid connection 36, thereby extending piston rod 28 and lengthening the boom. Simultaneously, the piston rod action, acting through link 38, will lower the boom pivotally. In essence, the boom, standard 6, and link 38 form a triangular structure, the leg of said triangle formed by standard 6 be fixed and the leg formed by the boom being of adjustable length. Thus when the length of the boom

is increased or decreased by cylinder 20, the angularity of the boom and link relative to the fixed leg must change. Conversely, when fluid is delivered to cylinder 20 through connection 34, the boom is simultaneously raised and shortened. It is of course obvious that the actual digging movement of bucket may be the component result of simultaneous operation of all three cylinders.

Certain advantages of this boom mechanism are believed clear. For example, when starting the digging of a hole at ground level, the boom is relatively short, and the bucket is therefore relatively close to standard 6 and hence to the machine operator. As the depth of the hole increases, the length of the boom is correspondingly increased. Thus a vertical-walled hole may be dug closer to the standard, and hence in better position to be viewed by the operator, than would be the case if the boom were of a fixed length corresponding to the depth of the hole to be dug. Also, as the boom is raised and shortened, the moment arm of the load carried thereby is decreased, thereby decreasing the power necessary to raise the boom and promoting ease of handling. When the boom is fully raised to its dumping or transporting position, its upward extension is at a minimum. This decreases or eliminates the topheavy nature of many machines of this type.

From an examination of the dotted line position of the boom in Fig. 1, it will be apparent that as the boom reaches its lowermost position, it approaches parallelism with link 38. If it were allowed to reach actual parallelism, then cylinder 20 could not raise the boom, since the lifting force would then be axial in link 38, or "dead center." To prevent this, and preserve an operating angularity between the boom and link 38, piston rod 28 is so proportioned in length that piston 26 will reach the limit of its travel at the forward end of cylinder 20, thus arresting the downward movement of the boom, while link 38 is still disposed angularly to the boom. If desired, other stop means could be employed. Also, it is apparent that the degree of extension or retraction of the boom for any given angular movement thereof depends on the vertical spacing between pivots 16 and 44, and could thus be altered by setting the bracket 42, which carries pivot 44, at different distances below bracket 18, or the

setting thereof could be adjustable. These as well as other minor changes of structure and operation could be made without departing from the spirit of the invention as defined by the scope of the appended claims.

5. What is claimed as new and desired to be protected by Letters Patent is:

1. In a digging machine, a boom supporting member, a boom comprising a plurality of sections longitudinally movable relative to each other, one end section of said boom being pivoted to said supporting member, digging members carried operatively by the other end section of said boom, a rigid member pivoted at one end to said other boom section and at its opposite end to said supporting member in spaced apart relation below said boom pivot, and power means interconnecting the end sections of said boom and operable to extend or retract said boom, whereby said boom is selectively raised or lowered.

2. In a digging machine, a boom supporting standard, a boom comprising inner and outer end sections slidably telescoped for relative longitudinal movement, said inner end section being pivoted to said standard, digging members carried operatively by said out end section, a hydraulic ram attached at its end respectively to said inner and outer boom sections whereby said boom may be extended or retracted, and a rigid link pivoted at one end to said outer boom section and at its opposite end to said standard at a point spaced below the pivotal connection of said boom to said standard, whereby said boom is lowered as it is extended and raised as it is retracted by said hydraulic ram.

3. The structure as set forth in claim 2 wherein said digging members comprise a bucket arm pivoted to said outer boom section, power means operative to pivot said bucket arm, a bucket pivoted to said bucket arm and opening toward said boom, and power means operable to pivot said bucket on said arm.
